UNITED STATES PATENT OFFICE

HARRY H. HONIGBAUM, OF NEW YORK, N. Y.

HOLDER FOR CIGARS OR CIGARETTES

Application filed February 5, 1930. Serial No. 425,984.

This invention relates to smoker's accessories and is directed more particularly to holders for cigars or cigarettes which in the preferred form of the invention have associated therewith receptacles for the collection of ash which, in the absence of such receptacles, would be apt to fall on the floor or on the person of the smoker. It is well known that during the smoking of a cigar or cigarette, ash accumulates rapidly at the burning end thereof and unless this ash is periodically deposited in an ash tray, it will fall upon the person of the smoker or upon the floor. Fastidious persons find it necessary under the present practice to invariably have an ash tray conveniently at hand for the disposal of such ash.

The primary object of the present invention is to provide a smoker's article which will serve the dual purpose of holding a cigar or cigarette and also provide for the receipt of ash therefrom.

Thus in the preferred form of the invention, the article embodies a clasp or holder adapted to embrace and hold the cigar or cigarette and with this clasp or holder is associated a receptacle or tray so positioned as to underlie the burning end of the cigar or cigarette so that as the ashes fall, they are caught in the tray. With the tray may be associated a substantially closed ash compartment in which the ash may be positioned in a manner to preclude spilling of the ash from the tray and this compartment may be emptied at convenient times to dispose of the ash contained therein.

The device of this invention is preferably employed in its entirety, but the invention is not limited to the employment of all the novel and useful features thereof, since some of the elements of the invention may be employed without necessarily employing them all. For example, the novel form of holder may be utilized without the associated tray or receptacle and the invention is therefore to be understood as fully commensurate with this inventive concept.

Features of the invention, other than those adverted to, will be apparent from the hereinafter detailed description and claims, when

read in conjunction with the accompanying drawing.

The accompanying drawing illustrates different practical embodiments of the invention, but the construction therein shown is to be understood as illustrative, only, and not as defining the limits of the invention.

Figure 1 is a side elevation of an article embodying the present invention.

Figure 2 is a section on the line 2—2 of Figure 1.

Referring to Figures 1 and 2, I have shown therein a combination cigar holder and tray made in accordance with this invention. All that portion of the article to the left of the line 1 is designated 2 and constitutes the holder portion and all that part to the right of the line 1 is designated 3 and constitutes the tray. The holder portion is in the form of a ring 4 sufficiently large to be slipped over a cigar or a cigarette as the case may be. In this connection, it will be noted that a relatively large size will be made for use with cigars and a correspondingly smaller size for use with cigarettes. The ring 4 fits very loosely in fact as not to contact therewith and from the rear edge of the ring extend spring tongues 5 and 6 which grip the cigar and hold the article thereon when the cigar is held between the lips. When, however, the cigar is carried in the hand, the spring tongues 5 and 6 are held between the fingers and the pressure of the fingers causes the tongues to grip the cigar even tighter, so that there is no possibility of disengagement of the article from the cigarette while they are being carried in the hand. A transverse finger piece 7 is preferably associated with the end tongue 6 to facilitate the holding of the tongues between the fingers and this part 7 also consists in supporting the device when it is laid upon a flat surface as it will serve to elevate the end of the cigar above said surface.

The forward edge of the ring 4 is extended to form a tray 3 which is flared out wider than the diameter of the ring, so that the burning end of the cigar will not contact with the walls of the tray. The upper portion of the tray is cut away as shown at 8

to provide an open top so that air may freely circulate about the burning end of the cigar. The forward end of the tray is in the form of a hooded receptacle to contain the ash which falls from the cigar. As the cigar is smoked, the article is periodically drawn back along the cigar so that the burning end will not engage with the article. Nevertheless such burning end will at all times be contained within the tray to catch the ash that may fall therefrom. Figures 1 and 2 show the arrangement for a cigar but the device may be made smaller to cooperate with a cigarette.

15 In the preferred form of the invention, a tray is associated with the holder and the tray may be made either rigid or may be so formed that it may be elongated or collapsed as desired. Furthermore, in the preferred 20 form of the invention, there is associated with the tray a receptacle from which ash received in the tray is deposited so that the interior of the receptacle is normally free from ash. Such a receptacle may be associated with any of the trays which I have 25 described and I preferably do so in practice.

I have clearly illustrated in Figs. 1 and 2 how the burning end of the cigar or cigarette is maintained free from contact with 30 the walls of the tray and while this is not essential, it is preferable.

The articles of this invention may be made from a wide variety of materials, but preferably are of fireproof materials. They may 35 be ornamented or left plain.

Having thus fully described the invention, what I claim as new and desire to secure by Letters Patent is:

1. As a new article of manufacture, a cigar 40 or cigarette holder comprising a substantially cylindrical part through which a cigar or cigarette is adapted to extend, one end of the cylindrical part being projected in the direction of its length to form an open top tray 45 adapted to underlie the burning end of the cigar or cigarette to receive ashes that may fall therefrom, and the other end of said cylindrical part being formed with gripping tongues extending rearwardly to respectively 50 overlap and underlie the cigar or cigarette to grip the same and preclude the inadvertent displacement of the holder from the cigar or cigarette, the tongue which underlies the cigar or cigarette being provided with a 55 transverse finger piece to preclude lateral tipping of the holder when resting upon a flat surface.

2. As a new article of manufacture, a cigar 60 or cigarette holder comprising a substantially cylindrical part through which a cigar or cigarette is adapted to extend, one end of the cylindrical part being projected in the direction of its length to form an open top tray adapted to underlie the burning end of the 65 cigar or cigarette to receive ashes that may

fall therefrom, the base of said tray being depressed below the base of the cylindrical member, so that the burning end of the cigar or cigarette will be spaced from the base of the tray.

In testimony whereof I have signed the foregoing specification.

HARRY H. HONIGBAUM.
